UNITED STATES PATENT OFFICE.

OBIE W. STARKS, OF CLEARFIELD, PENNSYLVANIA.

HANDLE MOUNTING FOR BRUSHES.

Application filed December 16, 1926. Serial No. 155,253.

The present invention relates generally to brushes, such as are commonly used for cleaning floors or walls, and which type of brushes are generally provided with handles of various lengths in accordance with the particular use to which the brush is applied.

The primary object of the present invention resides in the provision of a novel type of coupling whereby brushes, mops and the like, may be swivelly mounted upon handles for permitting of the brush proper to be adjusted relative to the handle.

A further object of the invention resides in the provision of a novel mounting or coupling means between the brush proper and handle therefor whereby the angular relation of the handle to the brush may be adjusted, and the position of the longitudinal or major axis of the brush proper adjusted with respect to the axis of the handle.

A further object of the invention resides in the provision of a novel type of handle mounting for brushes embodying novel locking features whereby the handle may be adjusted and locked at various angles of inclination with the brush proper, and which mounting also permits of the handle to be rotated about the brush proper and locked at any desired angle for permitting of the brush to be effectively used in close places or locations where it is desirable that the brush proper be disposed with its major axis at an angle to the axis of the handle.

A still further object of the invention is to provide a handle mounting for brushes which may be economically manufactured from sheet metal, thus providing a mounting which may be applied to brushes without materially increasing of the cost thereof.

Other objects and advantages of the invention will be apparent during the course of the following detailed description, taken in connection with the accompanying drawing forming a part of this specification and in which drawing.

Figure 1 is a side elevation showing the improved mounting or coupling applied to a conventional type of brush.

Figure 2 is a top plan view of the same.

Figure 3 is a fragmentary section on line 3-3 of Figure 2.

Figure 4 is a fragmentary section on line 4-4 of Figure 1.

Figure 5 is a perspective view of the catch

for retaining the handle in its adjusted angular relation to the brush proper.

Figure 6 is a perspective view of a key for permitting of the handle to be adjusted and locked at various angles with respect to the major axis of the brush proper.

Referring to the drawing in detail, and wherein similar reference characters designate corresponding parts thruout the several views, the letter A may designate a brush or mop of any suitable construction, and B the improved mounting or coupling for swivelly connecting of the brush A to the handle C.

The brush A in the example shown, embodies a head 10 of rectangular shape in plan, and which head serves as a carrier for the tufts of bristles 11. The brush A has merely been shown by way of example, one manner of use for the improved mounting, and it will be understood that the brush head 10 may serve for the supporting of other elements such as cotton strands or the like and not necessarily serve as a supporting means for bristles such as illustrated.

Referring now to the improved mounting or coupling B, the same embodies an attaching cap 12 whereby the handle C may be rotatably coupled to the brush A, and a quadrant 14 serving as means whereby the handle C may be adjusted into various angles with respect to the brush A.

Referring particularly now to the construction of the attaching cap 12, the same is preferably stamped from sheet metal of a suitable gauge for providing a bearing ring 15 provided at its lower edge with radially projecting feet 16 which are intended to engage flat upon the upper face of the brush head 10 and be secured thereto as by means of screws or other suitable fastening elements 17. Formed inwardly of the bearing ring 15, and disposed between the upper and lower edges thereof, is a pivot plate 18 provided with an axially disposed flanged opening 19.

As will be observed in Figure 3, this pivot plate 18 is formed as an integral part of the bearing ring 15 and provides a circular bearing seat 20 at the upper edge of the attaching cap which is reinforced by a doubling of the sheet metal from which the attaching cap is formed. Provided in the pivot plate 18, is an arcuate shaped slot 21

which extends for a distance slightly more than 180°, and which slot is struck from the axial center of the flanged opening 19. Open-

ing into the slot 21, and aligning transversely thereof, is a suitable number of notches 22, the terminally disposed notches preferably being disposed in alignment diametrically of the pivot plate 18. It is preferred, but not absolutely essential, that the attaching cap 12 be mounted upon the brush head 10 with the terminally aligning notches 22 extending parallel with the major axis of the brush head as illustrated in Figures 2 and 4, and which will dispose the arcuate shaped slot 21 to one side of the longitudinal center of the brush head.

Referring now to the specific construction of the quadrant 14, the same is preferably struck from sheet metal of a suitable gauge and embodies a bearing plate 25 provided at each longitudinal edge with upstanding parallel spaced apart quadrant plates 26. These quadrant plates 26 are adapted to pivotally receive therebetween, the handle C, the handle being pivotally connected by means of a suitable transverse bolt 27 extending thru the plates 26 at a point adjacent the forward lower portions of the plates. The handle C may be flattened as at 28 where it extends between the plates 26, and by so having the pivotal connection of the handle arranged as shown, the plates will not be subjected to any great strain when the brush A is being moved along the floor. Provided in each of the quadrant plates 26, and extending concentric with the pivot 27, are aligning arcuate shaped slots 30 provided with inner and outer recesses or notches 31 and 32 respectively, arranged in staggered relation thruout the length of the arcuate slots and opening into the slots as clearly shown in Figures 1 and 3. The inner notches 31 of one of the quadrant plates align with similar notches formed in the arcuate slot of the companion plate, while the outer notches 32 also align with similarly formed notches provided in the companion quadrant plate. By observing Figures 1 and 3, it will be seen that the bearing plate 25 is of greater length than the diameter of the bearing ring 15, and that the terminal portions of the bearing plates are intended to seat upon the bearing 20 provided at the upper edge of the ring 15.

A catch 35 is provided whereby the angular relation of the handle C may be adjusted with respect to the brush A. This catch 35 and which is intended to be slidably mounted upon the handle C, is of T-shape in formation and embodies a shank 36 provided at its forward end with a transversely extending head 37 the ends of which are intended to be moved into either the inner or outer recesses 31 and 32 which open into the arcuate shaped slot 30. The substantially flat shank portion 36 is provided with a longitudinally extending slot 38 thru which a suitable headed fastening element 39 may be passed and threaded into the handle C for slidably mounting of the catch

upon the upper face of the handle between the quadrant plates 26. The rear end of the catch 35 is preferably curled upwardly as at 40 for permitting of the ready sliding of the catch longitudinally along the handle C. Thus it will be seen that when the catch 35 is slid to a position whereby the ends of the head 37 align with the arcuate slots 30, that the handle C may be swung about its pivot point 27 for varying the angular relation of the handle with respect to the brush A, and when moved to the desired angle, the catch 36 may be slid longitudinally of the handle for moving the head 37 into locking engagement with either the inner or outer recesses 31 or 32 respectively.

The quadrant 14 is pivotally connected to the attaching cap 12 by means of a pivot bolt 45 which is passed thru the bearing plate 25 and extends loosely thru the flanged opening 19 of the pivot plate 18. As will be observed in Figure 3, this pivot bolt 45 is of less diameter than the inner diameter of the flanged opening 19 and which construction has been provided for permitting of slight tilting of the quadrant upon the attaching cap.

Rigidly secured to the bearing plate 25 to the rear of the pivot bolt 45, and extending below the bearing plate, is a key 46 of special formation, and which key serves for adjustably locking the handle C with its axis in various angular positions with respect to the major axis of the brush head A. This key 46, and which may be formed of a single construction, embodies an arcuate shaped guide plate 48 provided centrally of its end with an upwardly extending shank portion 49 which may be secured to the bearing plate 25 as by means of a nut 50. Projecting from each side of the arcuate shaped guide plate 48, adjacent the upper edge thereof, and preferably arranged at the longitudinal center of the plate, are aligning ears 51 which are adapted for fitting into the aligning notches 22 for locking the quadrant 14 at various locations of rotation upon the attaching cap 12. This arcuate shaped guide plate 48 is intended to move in the arcuate shaped slot 21, and when desiring to adjust the position of the quadrant 14, the quadrant is sprung upwardly by means of the handle C as illustrated in Figure 3, and which upward springing of the quadrant will allow the ears 51 to move free of the slot 21 and be guided across the upper face of the pivot plate 18 to the desired location whereby upon releasing of upward pressure on the handle, the ears 51 will again engage in the desired recess 22 for retaining the quadrant and handle in the desired angular position. The sheet metal of which the sections 12 and 14 are formed, will permit of this slight relative yielding for moving of the ears 51 out of locking engagement with either of the aligning recesses 22.

When desiring to adjust the angular rela-

tion of the handle C to the brush head 10, the catch 35 is first slid longitudinally along the handle so that the arms of the head 37 align with the arcuate shaped slots 30, and in which 5 position the handle C may be readily swung about its pivot 27 to the desired angle and after which the catch 35 may be slid into either of the recesses 31 or 32 for locking the handle in the desired angular position. When 10 desiring to rotate the handle C upon the brush head 10, the pivot bolt 45 will permit of the quadrants 14 to be tilted so as to lift the ears 51 out of the notches 22 of the slot 21 and thus permitting the handle to be adjusted 15 relative to the brush head for disposing the longitudinal or major axis of the brush head in the desired adjusted position with respect to the axis of the handle C.

From the foregoing description it will be 20 apparent that a novel and efficient handle mounting for brushes, mops and the like has been provided, which is of extremely simple and durable construction, and which is of such construction as to permit of the angular 25 relation of a handle to be adjusted into various positions with respect to the brush head, and embodying locking means whereby the handle is retained in either of its various adjusted positions with respect to the brush 30 proper.

Changes in detail may be made to the specific form of the invention herein shown and described, without departing from the spirit of the invention or the scope of the following 35 claims.

I claim:

1. In a handle mounting for brushes, an 40 attaching cap for connection with the brush head and provided with an arcuate shaped slot and notches opening into the slot, a quadrant, means mounting said quadrant upon the attaching cap so that it may be rotated and tilted with respect to said cap, a key 45 rigidly carried by said quadrant having a portion extending into said arcuate slot and provided with an ear for engaging in any one of said notches upon tilting, rotating and returning said quadrant to said cap for locking the quadrant at various degrees of rotation upon the attaching cap, and a handle 50 connected to said quadrant.

2. In a handle mounting for brushes, an 55 attaching cap for connection with the brush head embodying a bearing ring and a pivot plate provided with an arcuate shaped slot and notches opening into the slot, a quadrant pivotally connected to the pivot plate and

resting upon said bearing ring, a key rigidly carried by said quadrant inwardly of the bearing ring for arcuate movement in said slot 60 and provided with ears for engaging in said notches for locking the quadrant at various degrees of rotation upon the attaching cap, means for pivotally connecting a handle at one end to said quadrant, and means for adjustably retaining said handle in various angular positions with respect to the quadrant.

3. In a handle mounting for brushes, an attaching cap for connection with the brush head comprising a bearing ring and a pivot 70 plate arranged inwardly of the bearing ring and disposed below the upper edge thereof, said pivot plate being provided with an arcuate shaped slot having notches opening thereto, a quadrant pivotally mounted axially 75 of the pivot plate and yieldably engaging the upper edge of the bearing ring, a key rigidly carried by the quadrant inwardly of the bearing ring, embodying an arcuate shaped guide plate movable in the arcuate shaped slot of 80 the pivot plate and provided at its upper edge with laterally projecting ears for engaging in said notches of the arcuate shaped slot for locking of the quadrant at various degrees of 85 rotation upon the attaching cap, and means for pivotally connecting a handle at one end to said quadrant.

4. In a handle mounting for brushes, an attaching cap stamped from sheet metal, embodying a bearing ring having feet projecting from the lower edge thereof for attachment to the brush head and a pivot plate arranged inwardly of the bearing ring below the upper edge thereof and provided with an axially disposed flanged opening, said pivot 90 plate being provided with a semi-circular shaped slot arranged concentric with the flanged opening and having notches opening into the slot, a quadrant, a pivot member extending thru said flanged opening and quadrant for rotatably mounting of the quadrant upon the attaching cap, a key rigidly carried by the quadrant embodying an arcuate guide plate movable in said semi-circular shaped slot and provided at its upper edge with laterally projecting ears for locking engagement in the notches of the semi-circular shaped slot, and means for pivotally connecting a 95 handle at one end to said quadrant with the pivotal axis of the handle at a right angle 100 to the axis of the pivot member for the quadrant.
